DESIGN FOR A FIRE-PLACE.

Design No. 13,307, dated September 19, 1882.

UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A FIRE-PLACE.

SPECIFICATION forming part of Design No. 13,307, dated September 19, 1882.

Application filed August 11, 1882. Term of patent 7 years.

To all whom it may concern:

Be it known that I, WILLIAM TWEEDDALE, of Brooklyn, in the State of New York, have invented a Design for Fire-Place and Grate, 5 of which the following is a specification.

This design relates to the fender, the fire-place frame, and the fuel-holder or grate, the ornamentation on all of these having reference to the production of certain artistic effect.

10 The wheel-patterns that form the prominent ornaments of the fender and grate-frame are combined with bars and scrolls, as shown. The bars *a b c* and base *d* and the posts *e* form the open-work of the fender. The wheel ornaments *h* are introduced between the bars *b c*. The scroll and diagonal bar ornaments *g* are beneath the bar *a* at the sides of the posts *e*. Between the base *d* and bar *e* there are the wheel ornaments *f*, the diagonal bar and leaflet 15 ornaments *k*, and the round rails *i*, as shown.

20 The fire-place frame has arch molded borders *l*, sunk-surface wheel ornaments *n*, and diagonal pointed ornaments *o*.

The grate-frame or fuel-holder has the front 25 bar, *p*, scalloped at the lower edges, an arched

back plate, with scroll and leaflet ornaments *r*, as shown.

The fender-piece, grate, and fire-place frame compose a complete artistic design for a fire-place.

30

I claim as my invention—

1. The design of the fender-piece, consisting of the bars *a b c* and base *d*, posts *e*, wheel ornaments *h f*, leaflet and bar ornaments *k*, and rails *i*, substantially as shown.

2. The design of the fire-place frame, consisting of the arched molded border *l*, wheel ornaments *n*, and diagonal pointed ornaments *o*, substantially as shown.

3. The design of the grate-frame, consisting 40 of the bars *p*, with scalloped edges, the arched back plate, with scroll and leaflet ornaments, as represented.

* Signed by me this 7th day of August, A. D. 1882.

WILLIAM TWEEDDALE.
